DIAPHRAGM PUMP

Richard T. Cornelius, Minneapolis, Minn.

Application December 2, 1949, Serial No. 130,727

2 Claims. (Cl. 103—150)

1

My invention relates to diaphragm pumps and has for an object to produce a pump having great capacity for its size and weight.

Another object of the invention resides in providing a diaphragm pump which will be extremely compact in form.

A still further object of the invention resides in providing a diaphragm pump which can be constructed with a minimum amount of machining.

An object of the invention resides in constructing the pump with a body formed of molded plastic material and a head overlying said body and similarly constructed.

A feature of the invention resides in providing the body with a lateral wall structure and in further providing a partition in the body extending across the wall structure and dividing the interior body into two compartments elongated in form and in further constructing the said wall structure and partition with curved ends to form the compartments ovular in cross section.

An object of the invention resides in providing ovular pistons mounted in said compartments and in employing a single sheet of flexible material disposed between said head and body and forming a diaphragm for said pistons and a gasket between said head and body.

A still further object of the invention resides in providing a cap resting upon the upper end of the head and a base supporting the body, both said cap and base being constructed of cast metal and in further providing bolts engaging said cap and base and clamping the parts together to reduce undue strain on the molded plastic head and body.

Another object of the invention resides in mounting the crank shaft for operating the pistons of the pump in said base.

Another object of the invention resides in arranging said crank shaft at right angles to said partition and to the major axes of said pistons.

A still further object of the invention resides in providing valves in said head, one pair for each piston and in arranging said valves to overlie said pistons, the valves of each pair being disposed at opposite ends of the pistons to which they correspond, the valves at one end of each of the pistons being inlet valves and at the other ends being outlet valves.

Other objects of the invention reside in the novel combination and arrangement of parts and in the details of construction hereinafter illustrated and/or described.

In the drawings I have shown a diaphragm-

2

type pump particularly adapted for pumping water and similar liquids. This pump consists of a body having a lateral wall structure and formed with a partition dividing the interior of the body into two elongated compartments. The wall structure and partition are curved to form the compartments ovular in cross section. In each of the said compartments is disposed a piston ovular in form and conforming in configuration to the cross section of said compartments. Overlying the body is a head which conforms in shape to the body and between the head and body is a single sheet of flexible material which forms diaphragms for the pistons and a gasket between the head and body. In the head are formed inlet and outlet valves for each piston and which valves are arranged at the ends of the pistons. Both the body and head are formed of molded plastic material so as to have smooth and accurate surfaces of a configuration accommodating flexing of the diaphragm and without the requirement of machining. The body of the pump is mounted on a base constructed of cast metal. Overlying the head is a cap also constructed of cast metal. Bolts engaging the cap and base clamp the parts together. Carried by the base are bearings which rotatably support a crank shaft which extends at right angles to the partition. Mounted on said crank shaft are connecting rods which are connected to the pistons and which operate the same to procure the pumping action.

In the drawings:

Fig. 1 is a plan sectional view of a diaphragm pump illustrating an embodiment of the invention taken on line 1—1 of Fig. 3 and with part of the motor for driving the same illustrated.

Fig. 2 is an elevational sectional view taken substantially on line 2—2 of Fig. 1.

Fig. 3 is an elevational sectional view taken substantially on line 3—3 of Fig. 1.

In the manufacture of diaphragm pumps the common procedure has been to construct the parts of metal and to accurately machine the parts to produce the desired contours and form. To simplify machining, circular pistons and diaphragms have been employed which require appreciable space and give a minimum amount of capacity. Due to the impossibility of machining pumps utilizing other forms of diaphragms, only the circular type has been exploited to any extent and this type is exceedingly large for its capacity.

The disadvantages of such construction have been overcome in the pump disclosed in this application for patent by utilizing a mold-

ed plastic head and body in which the surfaces can be made irregular and accurately molded to the desired configuration and form and with extreme smoothness thereby completely eliminating the necessity of machining the irregular parts.

The invention proper consists of a diaphragm-type pump 10 which is mounted on a subbase 11. A motor 12, also mounted on the said subbase, serves to drive the pump. It will, however, be comprehended that the pump may be otherwise mounted and may be driven by any suitable source of motive power.

The subbase 11 is preferably constructed of sheet metal having a platform 13 with a lateral wall structure 14 extending downwardly therefrom. The lowermost portion of this wall structure is formed with an outwardly extending flange 15 which is adapted to rest on the surface on which the pump is to be mounted and through which suitable bolts or lag screws 16 may be inserted to clamp the base in position. The platform 13 has a depression 17 in the same which serves to collect any oil leaking from the pump proper and to discharge the same through the base through an opening 18 in said depression.

The motor 12 may be of any standard construction and description of the same will not be given in detail. This motor consists of a housing 19 and to which a base 20 is attached. Bolts 21 extending through said base and through the platform 13 of subbase 11 serve to attach the motor to the subbase. The motor has an armature shaft 22 which carries a sheave 23 and through which the pump is driven by means of a V-belt 24.

The pump proper consists of a base 25, a body 26 resting on said base, a head 27 overlying the said body and a cap 28 mounted on top of the head 27. These parts will now be described in detail.

The body 26 has a lateral wall structure 29 substantially rectangular in form to provide end walls 30 and 31 and side walls 32 and 33. These walls are constructed with spaced sections 34 and 35 which are connected together at their upper ends by means of webs 36. This type of construction reduces the amount of material required and at the same time gives an upper surface 37 to the wall structure of appreciable width. By means of this construction the resistance of the wall structure to compressive force is greatly increased. Extending transversely between the walls 32 and 33 is a transverse partition 38. This partition is similarly constructed with sections 39 and 40 and with a web 41 connecting the same together at their upper ends. The surface 42 of this web lies in continuation of the surface 37 of the wall structure 29 and the said surfaces lie in a common plane. By means of the construction provided two elongated compartments 43 and 44 are formed in the body 26 and which extend transversely of the same. The wall structure 29 and the partition 38 are curved at the ends of these compartments to give the said compartments an ovoidal cross section. The corners of the partition 38 and the wall structure 29 bounding the compartments 43 and 44 are rounded as indicated at 45. The entire body 26 is constructed from a molded plastic material which forms the surfaces 37 and 42 accurately and smoothly and which gives a rounded contour to the edges of the wall structure and partition bounding the compartments 43 and 44.

The base 25 is constructed of cast metal which may be cast iron or aluminum as found desirable. This base has a wall structure 46 corresponding in shape to the wall structure 29 of body 26 and which has end walls 47 and 48 and side walls 49 and 50. The upper edge of the wall structure 46 is formed with an inturned flange 51 on which the lower edges of the wall structure 29 of body 26 may rest. These parts are secured together as will be presently explained. The wall structure 46 rests upon the platform 13 of subbase 11 and is secured thereto by means of cap screws 52 which extend through said platform and are screwed into bosses 53 formed at the corners of the walls 47, 48, 49 and 50 of said base.

The head 27 consists of a lateral wall structure 54 which conforms in configuration to the wall structure 29 of body 26. This wall structure has end walls 55 and 56 and side walls 57 and 58. The said head further has an inner wall structure 59 which conforms to the inner sections 34 of wall structure 29 and to the sections 39 and 40 of partition 38 of body 26 and which is connected to the outer wall structure by means of webs 60. These webs have a surface 61 which faces the surfaces 37 and 42 of the body 26. The upper end of the wall structure 54 has a surface 62 which is parallel to the surface 61 and lies in a single plane.

Disposed between the surfaces 61 and the surfaces 37 and 42 is a sheet 63 of flexible material such as rubber or the like. This sheet is clamped in position between said surfaces as will be presently explained. Extending outwardly from the surfaces 61, 37 and 42 are beads 64 which bite into the rubber and hold the same in place and also assist in preventing leakage along the said surfaces.

Overlying the head 55 is the cap 28. This cap is dome-shaped in form having a top 65 and a circular wall structure 66. The wall structure 66 of the cap 28 is more nearly circular as shown in Fig. 1 as compared to the rectangular form of the wall structure 54 of head 27. At the corners between the said two parts are formed flanges 69. The lower end of the wall structure 66 and the flanges 69 have a surface 67 which corresponds with the surface 62 of head 27 and which faces the surfaces 62. A gasket 68 is disposed between these surfaces and forms a tight joint therebetween. Cap screws 70 extend through these flanges, through bosses 71 formed in the corners of the head 27 and through similar bosses 72 formed at the corners of the body 26. These cap screws are screwed into the bosses 53 formed at the corners of the base 25. These cap screws clamp the parts together and hold the sheet of material 63 tightly in position.

The base 25 supports a crank shaft 74. This crank shaft is rotatably mounted in two ball bearings 75 and 76 which are fitted into bores 77 in bosses 78 formed in the end walls 47 and 48 of the wall structure 46. Washers 129 overlie the edges of these bearings to restrain outward movement of the bearings and are held in position by means of screws 130 screwed into the bosses 78. The crank shaft 74 has a shaft extension 79 on which is mounted a fly wheel 80. This fly wheel is formed with a groove 81 which serves as a sheave and about which the V-belt 24 leading from motor 12 extends. By means of this construction the said crank shaft 74 is driven. The crank shaft 74 has two cranks 82 and 83 which are arranged so that the throw of the same is 180 degrees out of phase. Mounted on these

cranks are two connecting rods 84 and 85. The connecting rod 84 is disposed in compartment 43 while the connecting rod 85 is disposed in the compartment 44. The said connecting rods have mounted in them ball bearings 86 and 87 which in turn are mounted on the cranks 82 and 83. The connecting rods 84 and 85 are formed integral with pistons 88 and 89 which are oval in form and which conform to the shape of the compartments 43 and 44. These pistons have curved surfaces 90 which are adapted to engage the sheet 63 of flexible material. Issuing upwardly from the piston 88 are three studs 91. These studs are formed with heads 92 which are imbedded in bosses 93 formed integral with the said pistons. Overlying each of the pistons 88 and 89 is a follower 94 which has a curved surface 95 similar to the surfaces 90 of the pistons 88 and 89. The studs 91 pass through the follower 94 and the sheet 63 of insulated material. A screw 96 is screwed into the end of each of the studs 91 and has a washer 97 encircling it which bears against the end of each of said studs. In this manner the follower is maintained in position without unduly squeezing the rubber sheet 63. It will readily be comprehended that the portion of the sheet of rubber overlying the upper ends of the compartments 43 and 44 form diaphragms which when the shaft 74 is rotated flex back and forth to alternately compress and expand the fluid located above them.

In the wall structure 59 of the head 27 are formed two compartments 98 and 99. These compartments overlie the compartments 43 and 44 and form the compression chambers of the pump. In the cap 28 is provided a partition 101 which divides the space within said cap into two compartments 102 and 103. The compartment 102 serves as an inlet chamber and the compartment 103 as an outlet chamber. This partition 101 extends crosswise of the partition 38 and engages a raised portion 104 which has a surface 105 forming a continuation of the upper surface 62 of the head 27. The gasket 68 disposed between the surfaces 62 and 105 and between the corresponding surface 67 of the cap 28 forms a fluid-tight connection therebetween. In the cap 25 is formed a tapped inlet 109 which communicates with the compartment 102. The said cap is further formed with a tapped outlet 110 which communicates with the compartment 103.

The wall structure 59 has a top portion 111 which is formed with inlet ports 112 and with outlet ports 113. In the compartment 98 is disposed an inlet valve 114 which closes the port 112 allowing fluid to enter the chamber 98 but preventing the escape of fluid therefrom. An outlet valve 115 is located in the compartment 103 and is adapted to close the port 113 leading to compartment 98. This valve is similar to the valve 114 in construction. Similar inlet and outlet valves 114 and 115 are located in the compartment 99 and the compartment 103 and communicate with the compartments 102 and 99 through certain of the ports.

The valves 114 and 115 are all identical in construction and only one of the valves 114 which has been shown in detail in Fig. 2 will be described in detail. This valve consists of two discs of rubber 118 and 119 which are frusto-conical or dish-shaped in form. These discs are supported on formed backing members 120 and 121 which smoothly fit the interior of said discs. These backing members are mounted on a sleeve

122 which registers with the port 112. The said sleeve has openings 123 in the same which bring the ports 112 into communication with the space between the backing members 120 and 121. These backing members are further spaced from one another to form a slit 124 therebetween and through which the liquid may pass from the port 112 and into the compartment 98. The marginal portions of the discs 118 and 119 normally engage each other to prevent the flow of liquid into the valve but readily yield when the pressure is brought into the valve through the openings 123 and slit 124 to direct the water into the compartment 98. A retainer 125 engages the lowermost disc 119 at the lower part of the same while a crowfoot 126 is seated in an annular groove 127 in the wall structure 59 concentric with the port 112. A bolt 128 passes through the crowfoot 126 and the retainer 125 and clamps the parts in position and holds the valve attached to the top portion 111 of the wall structure 59. In addition this bolt clamps the innermost portions of the discs 118 and 119 against the backing members 120 and 121.

The operation of the invention is obvious. As the shaft 74 is driven the diaphragms formed by the flexible sheet 63 are flexed above and below the normal plane of said sheet. In this manner pressure and suction is alternately created in the compartments 98 and 99. When pressure is created in compartment 98 the discs 118 and 119 of valve 114 are squeezed together and no fluid escapes through the valve. However, the fluid is forced through the port 113 and into the interior of valve 115. This causes the marginal portions of the discs 118 and 119 to spread apart and the fluid enters the outlet compartment 103. The fluid is led from this compartment by any suitable means connected to the outlet 110. When the compartment 98 is under suction the reverse occurs. Valve 115 now remains closed and fluid may be drawn in through the port 112 and into the interior of the valve 114 where it escapes between the discs 118 and 119 and enters the compartment 98.

The advantages of the invention are manifest. The device is extremely simple in construction and foolproof in operation. By the use of the plastic body and head, machining of the surfaces contacting the sheet of rubber is eliminated thereby permitting of manufacturing the pump with a minimum amount of machining. The parts are held together by means of four bolts and whenever the sheet of flexible material wears the parts can be taken apart and a new sheet readily substituted. By means of the type of valve used, grains of sand may readily pass through the same without injuring the valve. Hence the entire pump will operate for an extremely long period of time without attention. Both of the bearings for the crank shaft are mounted in the base independently of the body or head. Thus the machining for the bearings becomes exceedingly simple and correct alignment of the balls receiving the ball bearing races may be procured without effort. The sheet of flexible material as well as forming diaphragms for the pump form a gasket sealing the head 27 and body 26. My improved pump by utilizing the oval-shaped pistons and piston chambers becomes exceedingly compact and utilizes a minimum amount of material.

Changes in the specific form of my invention, as herein described, may be made within the

scope of what is claimed without departing from the spirit of my invention.

Having described my invention, what I claim as new and desire to protect by Letters Patent is:

1. In a pump a body having a lateral wall structure forming a chamber therein open at the top, a partition in said body dividing said chamber into two compartments elongated in form, said wall structure and partition being curved at the ends of said compartments to make said compartments ovoidal in cross section, a piston in each of said compartments ovoidal in form, a head overlying said body and formed with a lateral wall structure and having portions disposed opposite the ends of the wall structure and partition of said body and forming two pressure compartments disposed above the first named compartments, a sheet of flexible material disposed between said head and body and engaging the ends of said wall structure and partition and said portions of the head and forming diaphragms for said pistons and a gasket between said body and head, a cap overlying said head and forming a space between said cap and said head, means on said cap and head forming a partition extending transversely of the partition in said body and dividing the space between said head and cap into an inlet compartment and an outlet compartment, outlet valves carried by the lateral wall structure of said head and disposed in said outlet compartment one on each side of said first named partition and bringing said respective pressure compartments into communication with said outlet compartment, inlet valves carried by the lateral wall structure and disposed on the side of said last named partition opposite said outlet valves and disposed one on each side of said first named partition and bringing said inlet compartment into communication with the respective pressure compartments and means carried by the body and connected to said pistons for reciprocating said pistons.

2. In a pump a body, a head carried by said body and having a lateral wall structure and a partition extending across the same and forming

therein two juxtaposed elongated pressure compartments open at the bottom, flexible sheet like means clamped between said head and body and closing said compartments, and forming diaphragms, pistons underlying said diaphragms, means carried by said body and connected to said pistons for reciprocating said pistons, followers overlying said diaphragms and secured to said piston, said followers being elongated in form and conforming in configuration to the configuration of said compartments, a cap overlying said head and forming a space therebetween, means forming a partition between said head and cap and extending transversely of the partition in said head, and dividing said space between said head and cap into an inlet compartment and an outlet compartment, outlet valves carried by the head and disposed in said outlet compartment one on each side of the partition in said head, and bringing the outlet compartment into communication with the respective pressure compartments, and inlet valves carried by the head and disposed on the side of said partition in said cap opposite said outlet valves and disposed in said pressure compartments and one on each side of the partition in said head, and bringing said inlet compartment into communication with the respective pressure compartments.

30
